UNITED STATES PATENT OFFICE

154,261

DESIGN FOR A LIQUID DISPENSING VALVE

Burdette B. Gilmore, Pelham Manor, N. Y., assignor to West Disinfecting Company, Long Island City, N. Y., a corporation of New York

Application June 28, 1947, Serial No. 139,993

Term of patent 14 years

(Cl. D4—3)

To all whom it may concern:

Be it known that I, Burdette B. Gilmore, a citizen of the United States and residing at Pelham Manor, in the County of Westchester and State of New York, have invented a new, original, and ornamental Design for Liquid Dispensing Valve, of which the following is a specification, reference being had to the accompanying drawings, forming part thereof, and in which

Fig. 1 is a top plan view of a liquid dispensing valve embodying my new design,

Fig. 2 is a side elevational view thereof,

Fig. 3 is a bottom plan view thereof,

Fig. 4 is a rear elevational view thereof, and

Fig. 5 is a front elevational view thereof.

I claim:

The ornamental design for a liquid dispensing valve, substantially as shown.

BURDETTE B. GILMORE.
